(57) **CLAIM**

The ornamental design for an immuno-chromatography inspection machine, as shown and described.

DESCRIPTION

FIG. 1 is a perspective view of an immuno-chromatography inspection machine, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a sectional view of FIG. 6 taken in the direction of line 8-8.

The broken lines shown in the drawings illustrate portions of the immuno chromatography inspection machine that form no part of the claimed design.

The dash-dot broken line defines the bounds of the partial sectional view and forms no part of the claimed design.
